BAG SEALING MACHINE

August E. Almgren, Hillside, John P. Jakob, Roselle, and Frank W. Goodrich, Newark, N. J., assignors to American Can Company, New York, N. Y., a corporation of New Jersey

Application December 17, 1947, Serial No. 792,124

13 Claims. (Cl. 53—102)

1

The present invention relates to a machine for sealing filled paper bags and other flexible containers and has particular reference to a multiple station machine arranged to receive a filled bag, seal it and then discharge it from the machine while traveling through a single cycle of operation. This is a companion application to our copending United States applications Serial Number 792,122, filed December 17, 1947, on Sealing Head Mechanism for Closing and Sealing Bags and Containers, now Patent No. 2,539,389, granted January 30, 1951; Ser. No. 792,123, filed December 17, 1947, on Bag Sealing Machine; Ser. No. 792,125, filed December 17, 1947, on Method of Sealing Bags, now Pat. No. 2,539,390, granted January 30, 1951; and Ser. No. 792,273, filed December 17, 1947, on Filling Machine, now Pat. No. 2,556,188, granted June 12, 1951.

Empty cans immediately upon manufacture are sometimes packed into large paper bags or other suitable flexible containers for protection against contamination during shipment and storage. The cans are placed in the bags manually or by machine and in either case are arranged in orderly rows and layers so that a substantially firm and solid package results when the bag is closed.

In packing the cans into the bag, it has been found that for best results, the bag should be held in a horizontal position so that the cans may be handled horizontally. However, in this horizontal filling position the bag is difficult to seal. For this reason the bag when filled usually is turned into an upright position for sealing. The filled bag is usually handled manually for effecting these operations.

The instant invention contemplates the provision of a continuously operating machine for handling and sealing these bags.

An object of the invention is the provision of a multiple station machine for sealing filled bags or other flexible containers wherein a filled bag is received directly from the filling machine, is turned into sealing position, is completely sealed and is discharged in one cycle of the machine thereby expediting the handling of the bags so that the high speed production of the machines that fill the bags may be maintained at their highest point of efficiency.

Another object is the provision of such a machine wherein the filled bags are handled entirely by the machine, thus eliminating all manual handling or transfer from one machine to another.

Numerous other objects and advantages of the

2

invention will be apparent as it is better understood from the following description, which, taken in connection with the accompanying drawings, discloses a preferred embodiment thereof.

5 Referring to the drawings:

Figure 1 is a sectional view of a bag handling machine embodying the instant invention, with parts broken away;

Fig. 2 is a top plan view of the machine shown in Fig. 1, with parts broken away;

Figs. 3 and 4 are horizontal sections taken substantially along the broken lines 3—3, 4—4 respectively in Fig. 1, with parts broken away;

Fig. 5 is a transverse section taken substantially along the line 5—5 in Fig. 2, with parts broken away;

Fig. 6 is an enlarged plan detail of a portion of the machine shown in Fig. 5, with parts broken away;

20 Fig. 7 is an enlarged front elevation of a portion of the machine at the left in Fig. 5 with certain of the parts in a different position, parts being broken away;

Fig. 8 is a sectional detail taken substantially along the line 8—8 in Fig. 1, with parts broken away;

Fig. 9 is an enlarged sectional detail taken substantially along the line 9—9 in Fig. 6, with parts broken away;

30 Figs. 10, 11 and 12 are sectional details taken substantially along the lines 10—10, 11—11, 12—12 respectively, in Fig. 4, with parts broken away;

Fig. 13 is an enlarged top plan view of a sealing head used in the machine and shown at the right in Fig. 5, with parts broken away;

Fig. 14 is a sectional view taken substantially along the line 14—14 in Fig. 13, with parts broken away;

40 Fig. 15 is an enlarged schematic perspective view showing the control devices and showing a piping diagram for fluid operated devices for actuating the sealing head, with parts broken away;

Fig. 16 is an enlarged sectional detail of one of a plurality of fluid slide valves included in the control devices shown in Fig. 15, with parts broken away;

Fig. 17 is an enlarged sectional detail of one of a plurality of fluid operated devices shown in Fig. 15, with parts broken away;

Fig. 18 is an enlarged perspective view illustrating the upper open end of a bag filled with cans preparatory to being sealed in the machine shown in Fig. 1;

Fig. 19 is a view similar to Fig. 18 showing the bag closed and sealed;

Figs. 20, 21 and 22 are enlarged perspective views showing a corner of a bag and illustrating how the marginal corner and marginal side sections are folded into sealing position; and

Fig. 23 is an enlarged sectional view showing a pleated corner fold taken substantially along the line 23-23 in Fig. 19.

As a preferred embodiment of the invention the drawings illustrate a multiple station sealing machine arranged to receive a bag or flexible container A (Fig. 18) filled with empty cans B, for sealing. The bag preferably is made of fibre material and in general is of a rectangular configuration as best shown in Figs. 18 and 19. When the bag is filled with cans, a marginal edge portion C of the bag extends beyond the cans a distance sufficient to permit folding of this portion inwardly against a flat sheet or closure member D for completely closing and sealing the bag. The closure member is inserted manually or in any other suitable manner, after the bag is filled. This closure member is provided with a band of adhesive or glue E on its outer surface, adjacent but in spaced relation to its outer periphery, for securing the folded portion of the bag to the closure member.

A bag to be sealed is received in a horizontal position, at a receiving station F (Fig. 2) and is first turned into an upright position at this station. The uprighted bag is then shifted along a curved path of travel through an idle station G, and into a sealing station H where the marginal edge portion C of the bag is folded inwardly and downwardly against the adhesive coated portions of the closure member D as best shown in Fig. 19. This seals the bag.

The folded over portions of the bag are held in place to insure complete bonding, while the bag is shifted along the same curved path of travel through two idle stations J, K and into a discharge station L. At the discharge station the pressure on the folded portions is released and the fully sealed bag is discharged from the machine and carried to any suitable place of discharge. This completes the cycle of operation of the machine.

The machine is of the rotary type, having the six stations F, G, H, J, K, L equally spaced and arranged in a circle around the machine. The filled bags A to be sealed are received and advanced through the stations progressively and intermittently, in sheet metal cradles 21 (Figs. 1 and 2) which are of rectangular shape to confine the bags. There are six of these cradles, one for each station, and they are moved through the different stations so that bags in different stages of sealing can be operated upon simultaneously.

Each cradle 21 is formed with a bottom 22 (see Figs. 1 and 7) three fixed side walls 23, and a hingeable front wall or door 24 secured by hinges to the bottom 22. The top of the cradle is open. When the door is closed it is locked by a latch 26 which is carried on a pivot pin 27 secured to a side wall 23 of the cradle. The latch is formed with a locking notch 28 which engages over a locking pin 29 secured to the door. The free end of the latch is tapered for engagement by the locking pin 29 when the door is hinged into closed position, to swing the latch to one side for engaging its locking notch with the locking pin. A pair of stop pins 31 carried on the

side wall of the cradle limits the swinging movement of the latch to prevent excessive overthrow.

Each cradle 21 is mounted in the machine in such a manner that it can be tilted into various positions for receiving, sealing, and discharging a bag A. For this purpose each cradle is secured to a U-shaped yoke or bracket 33 (Figs. 1 and 7) which extends across the bottom of the cradle and which is formed with legs which extend up along the two opposite side walls 23 of the cradle. The upper ends of the legs of the yoke carry trunnions 34 which are rotatably mounted in the upper ends of a U-shaped support bracket 35 disposed adjacent the yoke 33.

The support bracket 35 is mounted on the outer spread apart ends of a horizontal, bifurcated movable support member 36 (see Fig. 3). This member 36 is pivotally carried on the lower ends of two pairs of upright parallelogram links 37 (Fig. 1). There is one of these support brackets 35 and support members 36 for each cradle 21. The upper ends of all of the parallelogram links 37 are carried on pivot pins 38 secured in a horizontally disposed intermittently rotatable support disc or wheel 39 having a hub 41 freely mounted on a vertical stationary shaft 42. The upper end of the shaft is secured in a bearing 43 of a frame 44 mounted on a base plate 45 which constitutes the main frame of the machine. The lower end of the shaft is secured in a bearing 46 formed in the machine base plate.

Tilting of the cradles 21 is effected by a curved tilting lever 48 (Fig. 1) having one end pivotally connected to the cradle adjacent its door 24. The opposite end of the lever is pivotally connected to a lug 49 which extends down from the support disc 39. There is one of these tilting levers 48 for each cradle 21 and it moves with the cradle and the support disc.

The tilting of a cradle 21 is effected under pressure of a tension spring 51 (Fig. 1). There is one spring for each cradle. One end of the spring is secured to the hub 41 of the support disc. The opposite end of the spring is hooked over a rod 52, the ends of which are secured in the outer pair of support links 37.

The cradles 21 are intermittently moved into the stations F, G, H, J, K, L in succession by a conventional indexing device 55 (Figs. 1 and 8) located near the top of the machine. For this purpose the cradle support disc 39 is formed with a sleeve 56 which is an extension of the disc hub 41 and which extends up through a bearing 57 formed on a bracket 58 secured to the machine frame 44. At its upper end, adjacent the stationary shaft bearing 43, the sleeve carries an indexing wheel 61 having a plurality of depending cam rollers 62 arranged in a circle adjacent its outer periphery. There are six of these cam rollers, one for each station in the machine.

The cam rollers 62 are individually engageable in an interrupted cam groove 63 formed in a continuously rotating cam 64 mounted on a horizontal indexing shaft 65. The shaft is journaled in a plurality of bearings 66 secured to the machine frame 44. Rotation of the shaft is brought about by a sprocket 67 which is carried on its outer end. The sprocket is rotated by an endless chain 68 (see Fig. 2) which is driven by a sprocket 69 mounted on a main drive shaft 71 journaled in a bearing 72 carried on the machine base plate 45. The drive shaft may be driven in any suitable manner.

The cam groove 63 is shaped to engage one roller 62 at a time and for a portion of the rota-

tion of the cam 64 to advance or partially rotate the indexing wheel 61 and the cradle support disc 39 through one step to advance a cradle from one station to the next station. During the remainder of the rotation of the cam 64 its groove holds the engaged roller 62 and the parts of the machine controlled thereby, stationary to allow sufficient time to perform an operation on the bag in a cradle 21.

In the operation of the machine, the cycle of travel of a cradle 21, begins with its entry into the receiving station F for the reception of an unsealed bag A after just discharging a sealed bag at the discharge station L (see Fig. 2). This shifting of the cradle into the receiving station is effected by a partial rotation of the cradle support disc 39 by the indexing device 55 as just explained. The empty cradle enters the receiving station in a slightly tilted relation to the horizontal, with its door 24 partially open and riding on a stationary lifter cam 74 (Fig. 5).

When the cradle 21 comes to rest at the receiving station F, its support member 36 is swung outwardly on the support links 37 and this causes the tilting lever 48 to rock the cradle into a horizontal position as best shown in Fig. 1. This outward projection of the cradle into a horizontal position is effected by a shift rod 81 (Figs. 1 and 4) which is disposed in a horizontal position below the path of travel of the cradles. The rod is carried in a slide bearing 82 formed on the machine base 45 at the receiving station.

The outer end of the rod 81 is formed with a rounded head which engages against a curved shoe 83 which extends down from the outer ends of the bifurcated support member 36. There is one of these shoes for each cradle 21 and they are of sufficient length to form a complete circle around the machine when taken collectively. The cradle tension spring 51 holds the shoe against the rod. The inner end of the shift rod 81 engages against the free end of a cam lever 84 (Figs. 1, 4 and 12) carried on a pivot stud 85 secured in the machine base plate 45. This lever carries a cam roller 86 which operates against a continuously rotating edge cam or tilting cam 87 freely mounted on the vertical fixed shaft 42. A spring 88 keeps the roller in engagement with the cam. One end of the spring is secured in an arm 89 formed on the lever. The opposite end of the spring is hooked over a pin 91 secured in the machine base plate 45.

The edge cam 87 is rotated on the fixed shaft 42, once for each partial rotation of the cradle 21. For this purpose the cam is formed with a bevel gear 93 (Fig. 1) which meshes with and is driven by a bevel gear 94 mounted on the inner end of a short shaft 95 journaled in a pair of spaced bearings 96 formed on the machine base plate 45. The shaft is continuously rotated by an endless chain 97 (Figs. 2 and 3) which operates over a sprocket 98 (Fig. 1) mounted on the outer end of the shaft 95 and over a driving sprocket 99 (Fig. 2) carried on the main drive shaft 71.

In the outwardly projected horizontal position of the cradle 21 at the receiving station F, the open end of the cradle is facing outwardly and is in horizontal alignment with a bag loading mandrel or horn 101 (Figs. 1 and 2) which includes a plurality of horizontally disposed rods 102 on which an empty bag A is held while it is filled with the cans B. These rods are supported in a frame 103 which may be a part of a more elaborate machine for filling the cans into the bag. Such a machine is disclosed in United States Patent 1,950,370 issued March 6, 1934, to G. W.

Mudd on Packaging Machine and in the pending application, Serial Number 792,273, filed December 17, 1947, on Filling Machine by John P. Jakob, a co-applicant herein. The bags preferably are placed on the horn 101 manually.

When a bag A is filled with cans B, the cans and the bag, as a unit, are stripped from the horn bars 102 by a reciprocating pusher plate 104 (Figs. 1 and 2) which is disposed in front of the horn 101 in spaced relation thereto to permit the loading of cans into the bag. The pusher plate 104 is reciprocated through a forward or pushing stroke and thence through a return stroke by air or other fluid pressure. For this purpose the plate is mounted on the inner end of a piston rod 105 having a piston operating in a cylinder 106 secured to a bracket 107 bolted to the bag filling machine frame 103.

Compressed air or other suitable fluid is introduced into the cylinder by way of tubes 111, 112 (Fig. 1) which are connected to the cylinder at each end thereof and which communicate with the interior of the cylinder. These tubes 111, 112 lead to and are connected with a control valve 113 (Fig. 16) having a bore 114 containing a slide valve plunger 115. The ends of the plunger extend beyond the valve 113 and are formed with longitudinal vent channels 116, 117 which communicate with the outside atmosphere. Intermediate its ends the plunger is formed with an annular channel 118 which constantly communicates with a fluid inlet tube 119 secured in the valve 113. This inlet tube leads to a suitable supply of compressed air or other fluid under pressure.

The normal position of the valve plunger 115 in its valve 113 is shown in Fig. 16. In this position the lower end of the plunger blocks off communication between the tube 111 and the inlet tube 119 and vents the tube 111 and the cylinder 106 on one side of the piston, to the outside atmosphere by way of the plunger vent 116. The tube 112 is in communication with the inlet pipe 119 and therefore is conveying fluid under pressure to the cylinder on the opposite side of the piston. The vent 117 is out of register with the tube 112.

The plunger 115 is yieldably retained in this normal position by a spring 121 which is interposed between the outer end of the plunger and a retaining strap 122 secured to the valve. This spring presses the inner end of the plunger against a rotatable edge cam 123 (Fig. 15) which constitutes a member of a control mechanism 124. The cam is mounted on a continuously rotating cam shaft 125 (see also Fig. 1) journaled in a pair of spaced bearings 126 formed in a bracket 127 bolted to the top of the machine frame 44. The cam shaft 125 is rotated in time with the movement of the cradles 21 through the stations of the machine, one revolution for each stepped advancement, by an endless chain 128 (Fig. 1) which operates over a sprocket 129 on the cam shaft and over a driving sprocket 131 mounted on the indexing shaft 65.

Hence through its connection with the indexing shaft 65, the cam shaft 125 rotates the edge cam 123 and thus operates the valve 113 at the proper time to introduce fluid under pressure into the outer end of the cylinder 106. The entry of the fluid into this end of the cylinder forces the pusher plate 104 against the cans B in the bag A and thus pushes the cans and the bag as a unit, horizontally off the horn bars 102 and directly into the waiting cradle 21 at the receiving station F.

When the filled bag A is fully seated in the cradle 21, the door 24 is closed, while the pusher plate 104 returns to its original position in readiness for the next bag. The closing of the door is brought about by a fluid actuated closing pin 135 (Fig. 1) which is disposed at the receiving station and which is formed with a piston 136 located in a fluid cylinder 137 formed on a bracket 138 bolted to the machine base plate 45. A compression spring 141 disposed around the pin and interposed between the top of the cylinder and the piston, keeps the pin in a normally depressed position as shown in Fig. 1.

The lower end of the cylinder is in communication with and is connected by a tube 142 (see also Figs. 2 and 15) to a valve 143 which is similar to the valve 113 (Fig. 16) and which is connected to the fluid inlet tube 119. The valve is actuated by an edge cam 144 carried on the cam shaft 125 adjacent the cam 123.

The edge cam 144 operates the valve 143 at the proper time and thereby permits air from the inlet tube 119 to flow through the valve and into the cylinder 137. This fluid raises the closing pin 135 against the resistance of the spring 141 and thereby lifts the door up into closed position. During this upward travel of the door, its locking pin 29 engages the tapered nose of the latch 26 and pushes it to one side until the locking notch 28 engages over the locking pin 29 and thus securely locks the door in closed position. Upon locking of the door, the cam 144 closes the valve 143 and cuts off the supply of fluid. The spring 141 thereupon returns the closing pin 135 to its original lowered position in readiness for the next bag.

With the filled bag A locked securely in the cradle 21, the cradle is tilted into an upright position, as shown at the right in Fig. 1, while the cradle is still at the receiving station F. This tilting of the cradle is effected by the tilting cam 87 which rocks the lever 84 inwardly and thus relieves the pressure on the shift rod 81. This permits the cradle tension spring 51 to draw the cradle support member 36 inwardly and during this inward movement the tilting lever 84 rotates the cradle into its upright position.

When the cradle 21 is in a fully upright position, the indexing mechanism 55 turns the cradle support disc 39 through one step or partial rotation and thereby shifts the cradle 21 and its bag A into the idle station G. At this station the closure member D may be inserted into the bag. This preferably is a manual operation. During this same partial rotation an empty cradle 21 is shifted into the receiving station F. The filled upright cradle 21 at the idle station G remains stationary at this station until the empty cradle at the receiving station receives its filled bag and then the indexing mechanism 55 again turns the cradle support disc 39 through another partial rotation. During this second rotation, the upright cradle 21 shifts into the bag sealing station H.

The upright cradle 21 and its filled bag A entering the sealing station H comes to rest immediately below and in vertical alignment with a vertically movable sealing head 151 (see Figs. 2 and 5) for sealing the bag. The head includes a hollow rectangular shaped head frame 152 (see also Figs. 13 and 14) which is secured to a pair of depending legs 153 of an inverted U-shaped bracket 154 which extends across the top of the frame. The frame and the bracket are movably supported on a pair of side links 156 and a single

top link 157 which collectively form a parallelogram system of links which maintains the head in a level position while permitting vertical travel.

5 The outer ends of the two side links 156 are mounted on trunnions 158 which are formed on the lower ends of the bracket legs 153. The inner ends of these links are carried on pivot pins 159 (Fig. 5) secured in lugs 160 which extend down from a flange 161 formed on the upper end of the stationary bearing 57 of the bracket 53. The single top link 157 at its outer end is bifurcated and is mounted on a pivot pin 162 carried in a pair of spaced upright legs 163 formed on the bracket 154 and extending up inside of the bifurcated end of the link. The inner end of the link is mounted on a pivot pin 164 carried in the stationary lugs 160.

Vertical movement of the sealing head 151 is 20 effected by a vertical link 165 (Figs. 5 and 14) pivotally mounted on the pivot pin 162. The upper end of the link is pivotally connected to a piston rod 166 having a piston which operates within a vertically disposed cylinder 167 secured 25 to the main frame 44. The ends of the cylinder are connected by tubes 171, 172 to a valve 173 (Fig. 15) which is similar to the pusher plate valve 113 and which is connected to the fluid inlet pipe 119. This valve 173 is located adjacent 30 the valve 143 and is actuated by an edge cam 174 mounted adjacent the cam 144 on the cam shaft 125, to connect the tubes 171, 172 alternately with the fluid inlet tube 119.

When fluid under pressure passes through the 35 tube 171 into the upper end of the cylinder 167, the piston within the cylinder pushes the sealing head 151 down on top of the open end of the bag as best shown in Fig. 5. A tapered hood 175 (see also Fig. 14) secured to the bottom of the head 40 frame 152 guides the upstanding marginal edge portion C of the bag A into the head as the latter moves down over it for the sealing operation and thereby prevents crushing or distortion of this 45 portion of the bag. After the sealing operation the head 151 is raised to its normal elevated position by the action of the cam 174 on its valve 173, permitting fluid to enter the cylinder 167 through the tube 172 while venting the tube 171.

While the sealing head 151 is in sealing position 50 on the open end of the bag A, it folds the upstanding marginal edge portion C of the bag inwardly and downwardly against the adhesive coated portions of the closure member D and thus seals the bag. This folding operation preferably is effected in two stages, a corner folding stage and a side folding stage, to produce a 55 neat appearing fold as best shown in Fig. 19.

Folding of the corners of the upstanding marginal edge portion C is brought about by four triangular shaped corner folding elements 176 (Figs. 60 13, 20, 21 and 22) which are located one at each corner of the head frame 152 and which are normally in an upright position. These elements are mounted on pivot pins 177 carried in pairs 65 of spaced lugs 178 which project downwardly from the inside of the head frame at its corners. Each folding element is formed with a pair of spaced actuating arms 179 which are pivotally connected to the lower end of a link 181. The 70 upper end of the link is connected to a piston rod 182 (Figs. 15 and 17) having a piston 183 operates in a cylinder 184. There are four of these cylinders and they are located one at each corner of the head frame 152 and are secured to 75 the frame as shown in Fig. 17.

All four of the corner cylinders 184 (Fig. 15) are connected at their upper ends and are in communication with a fluid supply pipe 185 having a lead pipe 186 connected by a flexible tube 187 to a valve 188 which is similar to the valve 113 (Fig. 16) and which is located adjacent the valve 173. The lower ends of the cylinders 184 are connected by and are in communication with a fluid supply pipe 191 having a lead pipe 192 connected by a flexible tube 193 to the valve 188. The valve 188 like the other valves 113, 143, 173 is connected to the fluid inlet tube 119 and is operated to bring the supply pipes 186, 191 alternately into communication with the inlet tube 119. Actuation of the valve 188 is brought about by an edge cam 195 which is mounted on the cam shaft 125 adjacent the head actuating cam 174 as shown in Fig. 15 and is rotated by this shaft.

Hence during the rotation of the cam shaft 125, the edge cam 195 actuates the valve 188 to permit fluid under pressure from the main inlet tube 119 to flow through the lower supply pipe 191, while venting the upper supply pipe 185, and to enter all of the corner cylinders 184 simultaneously, below the pistons 183. This fluid pushes the pistons up and thereby simultaneously rocks all of the corner folding elements 176 inwardly and downwardly against the corners of the upstanding marginal edge portion C of the bag to be sealed, as best shown in Fig. 20.

This action of the corner folding elements 176 folds the corners of the marginal edge portion C inwardly and downwardly against the adhesive coated portion of the closure member D in the top of the bag. The corner elements 176 hold these corner sections in this folded position while the side portions of the marginal edge portion C are folded inwardly in a similar manner as will now be explained.

The side portions of the marginal edge portion C are folded into place by a plurality of side folding elements 197 (Figs. 13, 14, 20, 21 and 22) which are normally disposed in an upright position. These side folding elements 197 are located inside the head frame 152 and extend along the sides of the bag A to be sealed, from one corner element 176 to the other. Along the inner edge of the head, three are two short folding elements 197 with a clearance space between them as shown in Fig. 13. Each side folding element 197 is formed with a pair of spaced lugs 198 which are mounted on pivot pins 199 carried in a bracket 200 secured to the inner face of the head frame 152.

The side folding elements 197 are hinged toward and away from the bag A by arms 203 which are secured to the folding elements. There is one arm for each folding element. The outer end of each arm 203 (Figs. 14 and 21) is pivotally connected to an upright link 204, the upper end of which is pivotally connected to a piston rod 205 (Fig. 15) of a cylinder 206 carried on the head frame 152. There is one cylinder 206 for each folding element. These cylinders are similar in construction and operation to the corner folding cylinders 184 shown in Fig. 17.

The upper ends of all of the side folding cylinders 206 are connected by and are in communication with a fluid supply pipe 207 (Fig. 15) having a lead pipe 208 connected by a flexible tube 209 to a valve 211 which is similar to the valve 113 (Fig. 16) and which is located adjacent the valve 188. The lower ends of the cylinders 206 are connected by and are in communication with a fluid supply pipe 212 having a lead pipe 213 connected by a

flexible tube 214 to the valve 211. The valve 211 like the other valves 113, 143, 173, 188 is connected to the fluid inlet tube 119 and is operated to bring the supply pipes 207, 212 alternately into communication with the inlet tube 119. Actuation of the valve 211 is brought about by an edge cam 216 which is mounted on the cam shaft 125 adjacent the corner folding elements actuating cam 195 as shown in Fig. 15 and is rotated by this shaft.

Hence during the rotation of the cam shaft 125, the edge cam 216 actuates the valve 211 to permit fluid under pressure from the inlet tube 119 to flow through the lower supply pipe 212, while venting the upper supply pipe 207, and to enter all of the side folding cylinders 206 simultaneously, below the pistons in the cylinders. This fluid pushes the pistons up and thereby simultaneously rocks all of the side folding elements 197 inwardly and downwardly against the upstanding marginal edge portion C of the bag A as best shown in Fig. 21. This action of the side folding elements 197 folds the sides of the marginal edge portion C inwardly and downwardly against the adhesive coated portion of the closure member D in the top of the bag.

While the side folding elements 197 temporarily hold down the folded over side portions of the marginal edge portion C, the corner folding elements 176 are quickly lifted as shown in Fig. 22 to release their hold on the folded over corners of the edge portion C. This permits the folded over side portions, adjacent the corner portions to overlap the corner portions as shown in Fig. 22. The corner elements 176 are immediately pressed down again to crease these overlapping sections of the side portions to provide a neat appearing corner fold as best shown in Fig. 23. This action of the corner folding elements is brought about by the cam 195 during its operation of the valve 188.

While the folded over sections of the marginal edge portion C of the bag are temporarily held in place by the corner folding elements 176 and the side folding elements 197, the inner edges of this portion are pressed down against the closure member D to complete the sealing of the bag. This is brought about by a rectangular shaped sealing pad 221 (Figs. 1, 5, 13 and 14) which is disposed in a normally raised position, as shown at the left in Fig. 5, above the cradle 21 when it is in an uprighted position. There is one of the sealing pads for each cradle and it moves with the cradle in its travel through the stations of the machine. The pad is of proper proportions to fit within the outline defined by the inner edges of the closed corner and side folding elements 176, 197 respectively and is arranged to permit lowering of the sealing head 151 over the pad.

Each of the sealing pads 221 is formed with an inwardly projecting lever 222 which when the sealing head 151 is down, extends through a clearance opening 223 in the head frame 152 (see Figs. 13 and 14). The levers 222 of the pads, intermediate their ends, are mounted on pivot pins 224 (Figs. 5 and 6) carried in lugs 225 which extend up from the top of the cradle support disc 39. There is one pair of lugs for each lever and they are disposed adjacent the six cradles and move with the support disc. The inner ends of the levers 222 carry cam rollers 226 which when the support disc 39 rotates, traverse an interrupted cam groove 227 of a stationary barrel cam 228. The cam surrounds the sleeve 56 of

the support disc and is secured to the bottom of the stationary bearing 57 of the bracket 58.

The sealing pad 221 is moved down into clamping position on top of the bag A while the bag is at rest at the sealing station H. For this purpose, a cam roller 226 while at the sealing station, rests in a vertically movable slide 231 (Figs. 5, 6 and 9) mounted in a slideway 232 formed in the outer edge of the cam 228 and disposed between the upper and lower level ends of the interrupted cam groove 227. The slide is formed with a short cam groove 233 (Fig. 5) which normally is in register with the lower level end of the cam groove 227 so that as a roller 226 enters the sealing station it readily travels from the lower level end of the groove 227 into the slide groove 233.

At the proper time, the slide 231 moves up in its slideway 232 and thus carries the cam roller 226 vertically into alignment with the upper level end of the cam groove 227. It is this vertical travel of the roller, that rocks the lever 222 and thus moves the sealing pad 221 down onto the bag to complete the sealing operation.

This vertical movement of the cam slide 231 is effected by a piston rod 235 (Fig. 5) which is connected to the slide and which is formed with a piston located in a cylinder 236 attached to the flange 161 of the stationary bracket 58. The ends of the cylinder are connected by and are in communication with tubes 237, 238 to a valve 239 which is similar to the valve 113 (Fig. 15). The valve 239 like the other valves 113, 143, 173, 188, 211 is connected to the fluid inlet tube 119 and is operated to bring the tubes 237, 238 alternately into communication with the inlet tube 119. Actuation of the valve 239 is brought about by an edge cam 241 which is mounted on the cam shaft 125 adjacent the side folding element actuating cam 216 as shown in Fig. 15 and is rotated by this shaft.

As soon as the sealing pad 221 is in place on the bag A to hold the folded over portions of the bag, the sealing head 151 moves up out of the way where it is clear of the bag and the pad. This is brought about by its cylinder 167. The cradle 21 is then shifted into and through the two idle stations J, K. During this travel of the cradle and the bag, the pad cam roller 226 rides out of the slide groove 233 and into and along the upper level portion of the cam groove 227. Hence the sealing pad 221 remains in engagement with the folded over portions of the bag and thus insures complete bonding of these parts with the closure member D. The cam slide 231 returns to its lower level as soon as the cam roller 226 moves out of it, so that the slide will be in proper position to receive the next roller as it enters the sealing station H with its cradle and bag.

As the cradle 21, with its now completely sealed bag A, leaves the idle station K for entry into the discharge station L, the sealing pad 221 is lifted clear of the bag by an inclined section of the cam groove 227 which slopes down from the upper level to its lower level. The pad remains in this elevated position until it again enters the sealing station H on the next cycle of operation of the machine.

As the cradle approaches the discharge station L, the tapered nose of the door locking latch 26 rides up on a stationary inclined cam 243 (Figs. 2 and 7) secured to the machine frame 44 and thus lifts the latch so that it releases the cradle door 24 and permits it to swing open just as the

cradle comes to rest at the discharge station. The door falls down into engagement with the lower end of the door support cam 14 (Fig. 5) hereinbefore mentioned. The open door forms an inclined discharge chute which in this position is in alignment with one end of a continuously moving discharge belt conveyor 247 (Figs. 2 and 5). The machine end of the belt operates over a pulley 248 mounted on a shaft 249 carried in a bracket 250 secured to the machine base plate 45. The bracket 250 supports the cam 14. The conveyor is operated in any suitable manner.

As the door 24 on the cradle 21 falls open, the cradle itself is tilted forward to the angular position shown in Fig. 5 and thus throws or discharges the sealed bag A out onto the conveyor for removal to any suitable place of deposit. This tilting of the cradle into its angular position is effected while the cradle support disc 39 is stationary between its partial rotations and is brought about by a partial outward projection of the cradle support member 36. For this purpose the curved shoe 83 which extends down from the support member 36 is engaged and pushed outwardly against the resistance of the cradle tension spring 51 by the outer end of an auxiliary shift rod 255 (Figs. 4, 5 and 11) which is disposed in a horizontal position below the path of travel of the cradles. The rod is carried in a slide bearing 256 formed on the machine base 45 at the discharge station L.

The inner end of the auxiliary shift rod 255 engages against the free end of a cam lever 257 (Figs. 4 and 11) carried on a pivot stud 258 secured in the machine base plate 45. This lever carries a depending cam roller 259 which operates against a continuously rotating edge cam or tilting cam 261 which is integral with the tilting cam 87 and which rotates with this cam once for each partial rotation of the cradle. A spring 262 keeps the roller in engagement with the cam. One end of the spring is secured in an arm 263 formed on the lever. The opposite end of the spring is hooked over a pin 264 secured in the machine base plate 45.

After the discharge of the sealed bag A from the cradle 21, the auxiliary shift rod 255 is retracted to its original position in readiness for the next cradle and its sealed bag. However, the cradle from which the bag has been discharged, remains in its outwardly and angularly projected position for transfer in this position to the receiving station F where it is further shifted into a horizontal position as hereinbefore explained, to start a new cycle of travel.

This holding of the cradle in its angularly disposed position is effected by a retaining roller 266 (Figs. 4 and 10) which is normally disposed below the path of travel of the curved shoe 83 on the cradle support member 36 but which is moved up into engagement with the shoe, upon its outward projection at the discharge station, to hold it in this position. This roller is mounted on the upper end of an actuating pin 267 carried in a slide bearing 268 formed in the machine base plate 45. The lower end of the pin is pivotally connected to a cam lever 269 which is mounted on a pivot pin 271 carried in the machine base plate. The inner end of the cam lever 269 carries a cam roller 272 which operates against the lower face of the tilting cam 261. This face of the cam is formed to rock the cam lever 269 at the proper time in the rotation of the cam 261.

The retaining roller 266 is located beyond the auxiliary shift rod 255 in a position where it

holds the shoe 83 in a projected position during the movement of the shoe while the empty cradle 21 is passing from the discharge station L into the receiving station F to begin another cycle of travel. As the empty cradle approaches the receiving station, the shoe comes into engagement with the outer end of the shift rod 81. The support of the shoe is thereby transferred from the retaining roller 266 to the shift rod 81. The roller is then depressed in readiness for the next incoming cradle and shoe 83. This completes a cycle of operation of the machine.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In a machine for sealing a bag or other flexible container filled with articles, the combination of a holder for a bag filled with articles, transfer means disposed adjacent said holder for removing said filled bag from said holder, a cradle movable along a substantially horizontal path of travel adjacent said holder, means for moving said cradle along its path of travel, and means for tilting said cradle and for reciprocating it laterally relative to its path of travel into different positions including a position for receiving said bag from said transfer means, a bag sealing position and other positions for subsequent treatment of said bag.

2. In a machine for sealing a bag or other flexible container filled with articles, the combination of a holder for supporting a horizontally disposed bag filled with articles, transfer means disposed adjacent said holder for removing said filled bag from said holder, a cradle movable along a horizontal path of travel extending laterally of said holder, means for moving said cradle along its path of travel, and means for vertically rotating said cradle relative to its horizontal path of travel into different positions including a substantially horizontal position for receiving said bag from said transfer means, a bag sealing position, and other positions for subsequent treatment of said bag.

3. In a machine for sealing a bag or other flexible container filled with articles, the combination of a holder for a bag filled with articles, transfer means disposed adjacent said holder for removing said filled bag from said holder, a cradle movable along a path of travel extending through a plurality of stations including a receiving station disposed adjacent said holder, a bag sealing station and a discharge station, a door on said cradle, means for moving said cradle intermittently into and through said stations, means operable against said cradle door while the cradle is at said receiving station for closing said door, means adjacent said discharge station for opening said door to facilitate discharge of a sealed bag from said cradle, means for shifting said cradle into position for receiving the filled bag from said holder, and means for thereafter shifting said cradle and the bag received therein into bag sealing and discharge positions at said bag sealing and discharge stations, respectively.

4. In a machine for sealing a bag or other flexible container filled with articles, the combination of a holder for a bag filled with articles,

transfer means disposed adjacent said holder for removing said filled bag from said holder, a cradle movable along a path of travel extending through a plurality of stations including a receiving station disposed adjacent said transfer means, a bag sealing station and a discharge station, a door on said cradle, a lock on said cradle to secure said door in closed position, means for moving said cradle intermittently into and through said stations, means operable against said cradle door while the cradle is at said receiving station for closing and locking said cradle door, means adjacent said discharge station for unlocking and opening said door to facilitate discharge of a sealed bag from the cradle, means for shifting said cradle into position for receiving the filled bag from said transfer means, and means for thereafter shifting said cradle and the bag received therein into bag sealing and discharge positions at said bag sealing and discharge stations, respectively.

5. In a machine for sealing a bag or other flexible container filled with articles, the combination of a holder for a bag filled with articles, transfer means disposed adjacent said holder for removing said filled bag from said holder, a cradle movable along a path of travel extending through a plurality of stations including a receiving station disposed adjacent said holder and a sealing station and a discharge station removed from said holder, means for moving said cradle intermittently into and through said stations, means at said receiving station and operable on said cradle for shifting said cradle into a horizontal position for receiving the filled bag from said holder, means operable on said cradle at said receiving station for shifting the cradle and the bag therein into a vertical position for sealing, a sealing head at said sealing station for sealing said bag, and means at said discharge station and operable on said cradle for shifting said cradle into a position for discharging the sealed bag therefrom.

6. In a machine for sealing a bag or other flexible container filled with articles, the combination of a cradle movable along a path of travel extending through a plurality of stations including a receiving station and a sealing station and a discharge station, means for moving said cradle intermittently into and through said stations, means at said receiving station and operable on said cradle for shifting said cradle into a horizontal position for receiving a filled bag, means operable on said cradle at said receiving station for shifting the cradle and the bag therein into a vertical position for sealing, a sealing head at said sealing station for sealing said bag, and means at said discharge station and operable on said cradle for shifting said cradle into a position for discharging the sealed bag therefrom.

7. In a machine for sealing a bag or other flexible container filled with articles, the combination of an intermittently rotatable member, a movable support carried on said member and rotatable with said member through a curved path of travel extending through a plurality of spaced stations including a receiving station and a sealing and a discharge station, a cradle carried on said support for receiving and holding a filled bag to be sealed, means at said receiving station and at said discharge station for shifting said support relative to said rotatable member, and means operable against said cradle through the movement of said support for shifting said cradle into different positions including posi-

tions for receiving, sealing and discharging said filled bag.

8. In a machine for sealing a bag or other flexible container filled with articles, the combination of an intermittently rotatable member, a plurality of movable supports carried on said member and rotatable with said member through a curved path of travel extending through a plurality of spaced stations including a receiving station and a sealing and a discharge station, a cradle carried on each of said supports for receiving and holding a filled bag to be sealed, means at said receiving station and at said discharge station for shifting said supports successively relative to said rotatable member, and means operable against said cradles through the movement of said supports for shifting said cradles into different positions for receiving, sealing and discharging said filled bag.

9. In a machine for sealing a bag or other flexible container filled with articles, the combination of a rotatable member, indexing means for rotating said member intermittently through a step-by-step cycle, a movable support carried on said member and rotatable with said member through a curved path of travel extending through a plurality of spaced stations including a receiving station and a sealing and a discharge station, a cradle carried on said support for receiving and holding a filled bag to be sealed, means at said receiving station and at said discharge station for shifting said support relative to said rotatable member, means operable against said cradle through the movement of said support for shifting said cradle into different positions including positions for receiving, sealing and discharging said filled bag, and means for retaining said cradle in its discharge position for entry into said receiving station in this position.

10. In a machine for sealing a bag or other flexible container filled with articles, the combination of an intermittently rotatable member, a plurality of parallelogram links pivotally carried on said member, a movable support carried on said parallelogram links and rotatable with said member through a curved path of travel extending through a plurality of spaced stations including a receiving station and a sealing and a discharge station, a cradle pivotally mounted on said support for receiving and holding a filled bag to be sealed, spring means connecting said cradle with said rotatable member, means at said receiving station and at said discharge station for shifting said support relative to said rotatable member, and a tilting link connecting said cradle with said rotatable member for tilting said cradle with the movement of said support for shifting said cradle into different positions including positions for receiving, sealing and discharging said filled bag.

11. In a machine for sealing a bag or other flexible container filled with articles, the combination of a cradle movable along a path of travel for receiving and holding a filled bag to be sealed, said cradle having a bottom, an open top and side walls, one of said side walls being a door hingedly connected to said bottom and movable outward to facilitate reception of and discharge of said bag, latch devices carried on said cradle for locking said door in closed position, means for moving said cradle along its path of travel, means for shifting said cradle relative to its path of travel into different positions including a position for receiving said bag and other positions for sealing and discharging said bag,

means adjacent said path of travel and engageable with said door when the cradle is in a receiving position for closing and locking said door after reception of a bag in said cradle, and means engageable with said latch devices for unlocking said door when said cradle is in a discharge position for releasing the bag from said cradle.

12. In a machine for sealing a bag or other flexible container filled with articles, the combination of an intermittently rotatable member, a movable support carried on said member and rotatable with said member through a curved path of travel extending through a plurality of spaced stations including a receiving station and a sealing and a discharge station, a cradle carried on said support for receiving and holding a filled bag to be sealed, means at said receiving station and at said discharge station for shifting said support relative to said rotatable member, means operable against said cradle through the movement of said support for shifting said cradle into different positions including positions for receiving, sealing and discharging said filled bag, a sealing head at said sealing station for folding inwardly a marginal edge portion of said bag for sealing said bag, and a sealing pad carried on and rotatable with said member and disposed adjacent said cradle and movable at said sealing station into engagement with the folded marginal edge portion of the bag for holding said edge portion in sealing position for a predetermined travel of said cradle.

13. In a machine for sealing a bag or other flexible container filled with articles, the combination comprising a frame; a rotatable support mounted on said frame; support members radially reciprocal on said rotatable support; cradles pivotally mounted on said support members; tilting links connecting said cradles and rotatable support, each of said links having an end pivotally mounted on a cradle and its opposite end pivotally mounted on said rotatable support; bag transfer, sealing, and discharge mechanism on said frame and disposed respectively at transfer, sealing, and discharge stations located adjacent the path of said cradles when the latter are rotated with said rotatable support; and means for rotating said rotatable support, for actuating said bag transfer, sealing, and discharge mechanism, and for reciprocating said support members and cradles mounted on said rotatable support in timed relation one with the other so that each cradle is reciprocated and tilted to a horizontal bag receiving position at said transfer station, to a vertical position at said sealing station, and to an inclined position at said discharge station.

14. In a machine for sealing a bag or other flexible container filled with articles, the combination of a holder for supporting a horizontally disposed bag filled with articles, a cradle having a support therefor movably disposed adjacent said holder, said cradle having an open end alignable with said holder, transfer means adjacent said holder for transferring said bag bottom end foremost from said holder to said cradle when the open end of the cradle is in aligned position with said holder, and means for moving said cradle with and relative to its said support into different positions including said aligned position for receiving said bag from said holder and thence into a different bag sealing position.

15. In a machine for sealing a bag or other flexible container filled with articles, the com-

bination of a holder for supporting an empty bag in position for the reception of the articles, a cradle having a support therefor movably disposed adjacent said holder, said cradle having an open end alignable with said holder, transfer means adjacent said holder for inserting the articles into the empty bag and for transferring the filled bag bottom end foremost from said holder to said cradle when the open end of the cradle is in aligned position with said holder, said transfer means having a pusher plate movable through and beyond said holder for fully seating the filled bag in said cradle, and means for moving said cradle with and relative to its said support into different positions including said aligned position for receiving said bag from said holder, a bag sealing position and into other positions for subsequent treatment of said bag.

16. In a machine for sealing a bag or other flexible container filled with articles, the combination of a holder for supporting an empty bag in position for the reception of the articles, a cradle having a support therefor movably disposed adjacent said holder, said cradle being tiltably mounted on said support and having an open end alignable with said holder, transfer means adjacent said holder for inserting the articles into the empty bag and for simultaneously transferring the filled bag bottom end foremost from said holder to said cradle when the open end of the cradle is in aligned position with said holder, said transfer means having a pusher plate movable through and beyond said holder for fully seating the filled bag in said cradle, and means for tilting said cradle on its said movable support into different positions including said aligned position for receiving said bag from said holder, a bag sealing position and thereafter into other positions for subsequent treatment of said bag.

17. In a machine for sealing a bag or other flexible container filled with articles, the combination of a holder for supporting a horizontally disposed bag filled with articles, a cradle

having a support therefor movably disposed adjacent said holder, said cradle being pivotally mounted on said support and having an open end alignable with said holder, transfer means adjacent said holder for transferring said bag bottom end foremost from said holder to said cradle when the open end of the cradle is in aligned position with said holder, and means operable in time with said transfer means for tilting a cradle on its said support into different positions including said aligned position for receiving said bag, a bag sealing position and other positions for subsequent treatment of said bag.

18. In a machine for sealing a bag or other flexible container filled with articles, the combination of a holder for supporting a bag filled with articles, transfer means disposed adjacent said holder for removing said filled bag from said holder, a cradle having a support therefor movable along a path of travel adjacent said holder, said cradle being tiltably mounted on its said support and having an open end alignable with said transfer means, means for moving said cradle and its support along said path of travel, and means for tilting said cradle on its said support to align its open end with said transfer means for receiving said filled bag therefrom, and means for thereafter tilting said cradle on said support into a bag sealing position and into other positions for subsequent treatment of said bag.

AUGUST E. ALMGREN.
